UNITED STATES PATENT OFFICE.

HIRAM H. SPONENBURG, OF WADSWORTH, ILLINOIS, ASSIGNOR OF ONE-HALF TO EDWARD LAAS, OF ELGIN, ILLINOIS.

RAILWAY-RAIL STAY.

SPECIFICATION forming part of Letters Patent No. 738,499, dated September 8, 1903.

Application filed June 17, 1903. Serial No. 161,830. (No model.)

To all whom it may concern:

Be it known that I, HIRAM H. SPONENBURG, a citizen of the United States, and a resident of Wadsworth, in the county of Lake, in the 5 State of Illinois, have invented new and useful Improvements in Railway-Rail Stays, of which the following, taken in connection with the accompanying drawings, is a full, clear, and exact description.

10 This invention relates to the class of rail-stays which are designed to prevent longitudinal creeping of the rails on railways.

The object of the invention is to provide a rail-stay which shall be simple and inexpensive in construction and efficient in its operation; and to that end the invention consists, essentially, of a bar provided with an abutment engaging the cross-tie in opposition to the longitudinal movement of the rail, jaws 15 projecting from said bar, and a key inserted into one of said jaws and gripping the base of the rail between said key and opposite jaw; and the invention also consists in novel details of the construction of the rail-stay, as 20 hereinafter fully described, and set forth in the claims.

In the annexed drawings, Figure 1 is a front view of the improved rail-stay applied to the track-rail of a railroad. Fig. 2 is a 25 plan view of the same. Fig. 3 is an enlarged plan view of the rail-gripping key, and Fig. 4 is a transverse section on line X X in Fig. 3. *a* denotes the track-rail, and *b* one of the cross-ties which support said rail.

30 *c* represents a bar which extends across the under side of the rail *a* and is formed with a downwardly-projecting abutment *d*, which engages the side of the cross-tie *b* to prevent longitudinal movement of the rail *a*, 35 which is secured to said bar by means of my improved fastening devices, formed as follows, to wit: The top of the bar *c* is provided with rigid upwardly-projecting jaws *e* and *e'* at opposite sides of the rail *a* and preferably 40 formed integral with the bar. The two jaws are at a sufficient distance from each other to allow a space between the jaw *e* and edge of the adjacent flange of the rail, while the 45 other jaw, *e'*, engages the flange on the opposite side of the rail, as shown in Fig. 1 of the drawings. Into the jaw *e* is inserted a suit-

able key *f*, which is slightly tapered endwise, so that in driving the key into the jaw the base of the rail becomes firmly gripped between the said key and jaw *e* and prevents the rail *a* from creeping longitudinally by the resistance of the abutment *d* engaging the side of the cross-tie. To insure a more positive hold of the key on the rail, I provide the key with transverse notches *n*, forming teeth *o*, which bite the edges of the rail-flange and the interior of the jaw, so as to prevent accidental loosening of the key from its hold. I also prefer to form the key *f* with a longitudinal groove *g* to allow it to lap onto the top 60 of the engaged edge of the rail-flange and obtain additional hold on said flange.

The bar *c* with its abutment *d* and jaws *e*, in combination with the key or wedge *f*, constitute my improved rail-stay.

To allow the said rail-stay to be readily applied to a rail mounted and secured to the cross-ties, I form the top of the bar *c* with a depression *h* adjacent to the jaw *e*. This depression allows the rail-flange to enter the 70 jaw *e* and the bar *c* to be tilted endwise and shifted laterally to cause the jaw *e* to engage the rail-flange. After the bar is thus placed in position the key *f* is inserted and driven into the jaw *e* to obtain a firm hold on the 75 flange of the rail and on the inside of the jaw. If desired, the key may be applied in a vertical position, as indicated by dotted lines in Figs. 1 and 2 of the drawings.

What I claim as my invention is—

1. A railway-rail stay consisting of a bar provided with an abutment engaging the cross-tie in opposition to the longitudinal movement of the rail, jaws projecting from said bar, and a key inserted into one of said jaws and gripping the base of the rail between said key and opposite jaw as set forth.

2. A railway-rail stay consisting of a bar provided with an abutment engaging the side of the cross-tie, jaws projecting rigidly from the bar at opposite sides of the rail, and a key inserted into one of said jaws and gripping the base of the rail between said key and opposite jaw as set forth.

3. A railway-rail stay consisting of a bar formed with an abutment engaging the side of the cross-tie and with upwardly-projecting

jaws at opposite sides of the rail and a depression in the top of the bar adjacent to one of the jaws, and a key inserted into the latter jaw and gripping the base of the rail between said key and opposite jaw as set forth.

4. A railway-rail stay consisting of a bar formed with an abutment engaging the side of the cross-tie and with upwardly-projecting

jaws at opposite sides of the rail, and a rail-gripping key inserted into one of said jaws and formed with a longitudinal groove in the rail-gripping side as set forth.
